UNITED STATES PATENT OFFICE

2,522,040

MIXER FOR THE MAKING OF LIGHT CONCRETE

Matti Janhunen, Helsinki, Finland

Application August 7, 1947, Serial No. 766,977
In Finland August 24, 1943Section 1, Public Law 690, August 8, 1946
Patent expires August 24, 1963

5 Claims. (Cl. 259—178)

1

My invention relates to a mixer for use in making light concrete, the mixer having a drum provided with filling and discharge openings, a shaft extending within the drum, and mixing blades on the shaft.

According to my invention in a mixer as aforesaid the mixing blades extend substantially radially from the shaft and substantially from one end of the drum to the other in the direction of the shaft, and comprise wire netting, perforated plate or other perforated material.

In order that my invention may be clearly understood the following more specific embodiment will now be described but merely by way of example with reference to the accompanying drawing in which Fig. 1 is a longitudinal section and Fig. 2 is a transverse section.

In the drawing, 1 is the drum with a filling opening 2 and a discharge opening 3, and 4 is the shaft passing through the ends of the drum, the mixing blades 5 being fitted on the shaft by means of cruciform carriers 6 secured one at each end of the shaft. The four blades 5 extend radially from the shaft and are arranged at right-angles to each other, the blades consist of a single sheet of wire netting or network appropriately bent and extending continuously between the blades. The portion of the wire netting between each pair of adjacent blades is bent inwards to form a channel 7 which extends close to and parallel with the shaft 4. The outer edges of the blades 5 consist of metal strips 8 of U-shaped cross-section.

The arrangement is such that on rotation of the shaft 4 the blades 5 rotate and raise from the bottom of the drum the mass to be mixed and thus effect a thorough mixing of the ingredients of the concrete. The perforated blades 5 thus render the mixture porous. When increased porosity is desired air is conducted through the mass in a manner known per se.

I claim:

1. A concrete mixer for making light concrete, including the combination of a hollow drum having an inlet port and an outlet port; a shaft 45 rotatably supported transversely in the drum; a plurality of supporting members rigidly projecting radially from the shaft in spaced apart relation; and a wire network extending inwardly toward said shaft between each two adjacent supporting members from the outer ends of said supporting members and being attached to said outer ends.

2. A concrete mixer for making light concrete, including the combination of a hollow drum having an inlet port and an outlet port; a shaft 55 rotatably supported transversely in the drum; a

2

plurality of supporting members rigidly projecting radially from the shaft in spaced apart relation; and a plurality of pieces of network individually extending inwardly towards said shaft between each two adjacent supporting members from the outer ends of said supporting members and having the ends of said pieces of network secured to said outer ends.

3. A concrete mixer for making light concrete, 10 including the combination of a hollow drum having an inlet port and an outlet port; a shaft rotatably supported transversely in the drum; a single piece of network surrounding all of the supporting members and extending inwardly toward said shaft between each two adjacent supporting members from the outer ends of said supporting members and being secured to said outer ends.

4. A concrete mixer for making light concrete, 20 including the combination of a hollow drum having an inlet port and an outlet port; a shaft rotatably supported transversely in the drum; a plurality of wide supporting blades rigidly projecting radially from the shaft in angularly spaced apart relation; and a plurality of pieces of network individually extending inwardly toward said shaft between each two adjacent supporting blades from the outer ends of said supporting members and having the ends of each piece of network secured to the outer ends of the pair of supporting blades between which it is located.

5. A concrete mixer for making light concrete, 30 including the combination of a hollow drum having an inlet port and an outlet port; a shaft rotatably supported transversely in the drum; a plurality of wide supporting blades rigidly projecting radially from the shaft in angularly spaced apart relation; and a single piece of network surrounding all of the supporting blades and extending inwardly toward said shaft between each two adjacent supporting blades from the outer ends of said supporting members and being secured to said outer ends.

MATTI JANHUNEN.
